UNITED STATES PATENT OFFICE

143,420

DESIGN FOR AN INDUSTRIAL HAND TRUCK OR SIMILAR ARTICLE

Frank E. Gaines, Alhambra, Calif.

Application July 14, 1945, Serial No. 120,707

Term of patent 14 years

(Cl. D14—3)

To all whom it may concern:

Be it known that I, Frank E. Gaines, a citizen of the United States, residing in Alhambra, in the county of Los Angeles, State of California, have invented a new, original, and ornamental Design for an Industrial Hand Truck or Similar Article, of which the following is a specification, reference being had to the accompanying drawing, forming a part thereof.

Figure 1 is a perspective view of an industrial hand-truck embodying my novel design.

Figure 2 is a perspective view similar to Figure 1 but taken from a side opposite from that of Figure 1.

Figure 3 is a front elevational view of the industrial hand-truck.

Figure 4 is a rear elevational view taken from a side opposite from that of Figure 3.

Figure 5 is a plan view of the industrial hand-truck.

Figure 6 is a fragmentary plan view similar to Figure 5 but showing the parts for retaining a cylindrical object turned downwardly into the plane of the frame in an opposite extreme from the position shown in Figure 5.

I claim:

The ornamental design for an industrial hand truck or similar article, as shown.

FRANK E. GAINES.
